UNITED STATES PATENT OFFICE.

JAMES WOODS CASTLEMAN, OF WEST END, ALABAMA, ASSIGNOR OF ONE-HALF TO SOL. HAAS, OF BIRMINGHAM, ALABAMA.

APPARATUS FOR DUMPING CARS.

SPECIFICATION forming part of Letters Patent No. 658,760, dated October 2, 1900.

Application filed February 21, 1900. Serial No. 6,085. (No model.)

To all whom it may concern:

Be it known that I, JAMES WOODS CASTLEMAN, a citizen of the United States, and a resident of West End, in the county of Jefferson 5 and State of Alabama, have invented certain new and useful Improvements in Apparatus for Dumping Cars; and I do hereby declare the following to be a full, clear, and exact description of the same, reference being had to the accompanying drawings, forming a part 10 of this specification, and to the letters of reference marked thereon.

This invention relates to improvements in apparatus for dumping cars, and particularly 15 to that class in which the cars are run upon a track-section which is turned or tilted with the car thereon to dump the contents of the car; and it relates especially to an improved 20 form of counterbalancing mechanism where- by there will be less resistance to the tilting of the section during its initial movement, with an increasing resistance as the tilting movement continues.

The invention consists in certain novel 25 details of construction and combination and arrangements of parts, all as will be now described, and the particular features of novelty pointed out in the claims.

In the drawings, Figure 1 is a view, partly 30 in section, of a side-dumping track-section embodying the invention and showing in dotted lines the position the parts assume when at the forward extreme of this movement. Fig. 2 is a similar view showing the invention 35 applied to an end-dump system.

Similar letters of reference in both figures indicate the same parts.

Referring particularly to Fig. 1, A indicates the tilting platform or track-section, B beams 40 upon which track-rails b are laid, forming the continuation of the main-haulage track. C is a railing extending along each side of the platform and from which extends inwardly a guard-rail c, beneath which the wheels of the 45 car D pass. The platform A is carried by a longitudinal shaft E, journaled in suitable bearings, the axis being slightly to one side of the center line of the platform, as shown clearly in Fig. 1.

50 As thus far described, the apparatus may be similar in construction and operation to

those previously patented or used, and being well known needs no further description.

In devices of this character it is highly desirable that a counterweight be provided 55 which will offer little resistance to the initial-tilting movement of the platform, but will offer a gradually-increasing resistance as the tilting movement continues, so as to prevent an entire overturning of the platform. In the 60 accompanying drawings there is illustrated a practical embodiment of one form of such differential counterweight. As shown, it consists of a weighted car F, attached to the platform A by a suitable flexible connection, such as a 65 rope or cable G, running over a pulley I. The weighted car runs on a track H of varying inclination, said track being substantially horizontal or only slightly inclined for a portion of its length and then curving upwardly 70 until it assumes an approximately - perpendicular position, as shown clearly in the drawings.

The operation of the apparatus will now be understood. At the beginning of the tilting movement of the platform the weighted car offers but slight resistance as it then stands on the horizontal or slightly-inclined portion of the track, but as the movement of the platform continues and its momentum 75 increases the weighted car running up the steeper or more vertical portion of the track offers a proportionately-increasing resistance, thereby causing the tilting movement to be steady and gradual, the weighted car finally 80 stopping the movement when its whole weight is supported by the tilting section, thereby preventing the complete overturning of the car. As soon as the car is emptied the weighted car will overbalance the empty car 85 and tilting section and return them to their original position, ready to run off onto the main track. During the tilting of the platform it is desirable that the cable or rope to which the counterweight is attached should 90 at all times be held away from the axis of the platform as the point of attachment swings around the axis. To secure this result, there is attached to the under side of the platform a curved guide K, against which the rope or 95 cable will bear when the platform is tilted, as shown clearly in dotted lines, Fig. 1. It

will be noted that the curved guide K is eccentric to the axis of the platform. From this it results that the distance of the cable or rope carrying the counterweight from the 5 axis of the platform will increase as the platform is tilted, thereby adding to the effect of the counterweight, as will be readily understood. A lock or latch J automatically locks the platform when swung to initial position, 10 and said latch may be released when a car is in place and ready to be dumped by a cord or other releasing mechanism in convenient reach of the attendant.

In Fig. 2 the construction is similar to that 15 illustrated in Fig. 1, except that the invention is here applied to an end-dump system. In this construction the car L to be dumped is run on the tilting platform M, supported by pivots N and provided with the horns O, 20 of usual construction, the center of gravity of the section when a car is thereon being, as in the former instance, beyond the shaft N. The end of the car is closed by a door l, pivoted by links Q to the side of the car, and 25 the hoisting-rope R is attached to the door l at the top and runs over a sheave near the front of the car. When the car is tilted, the door will be retarded in its movement by the hoisting-rope, and the car, dropping away, 30 will open the end of the car and permit the contents to run out.

While the side-tilting-platform arrangement has been shown and described as adapted 35 to handle and dump single cars, this arrangement is equally adapted to the handling

and dumping of trips or trains of two or more cars without the necessity of uncoupling the cars from each other or from the haulage-rope. To accomplish this, all that is necessary is to increase the length of the tilting platform, depending upon the number of cars to be handled, and to correspondingly increase the weight of the traveling counterweight.

Having thus described my invention, what I claim as new, and desire to secure by Letters 45 Patent, is—

1. In an apparatus such as described, the combination with the tilting platform, of the counterweight, the flexible connection between the counterweight and platform, and the independent curved guide eccentric to the axis of the platform carried by said platform, upon which the flexible connection is guided as the platform is tilted; substantially as and for the purpose set forth.

2. In an apparatus such as described, the combination with the tilting platform, of the counterweight, the track or way of varying inclination upon which the counterweight travels, the flexible connection between the 60 tilting platform and counterweight, and the curved guide carried by the platform to which the flexible connection conforms as the platform is tilted; substantially as and for the purpose set forth.

JAMES WOODS CASTLEMAN.
